(57) **CLAIM**

The ornamental design for elastomeric bone cordage, as shown and described.

DESCRIPTION

FIG. 1 is a first side of a length of elastomeric bone cordage showing one section of a repeating pattern; and, FIG. 2 is a second side of a length of elastomeric bone cordage showing one section of a repeating pattern.

The portion of the elastomeric bone cordage in light contrast is environment and forms no part of the claimed design.
